(74) Attorney, Agent, or Firm — Dorsey & Whitney LLP

(57) **CLAIM**

The ornamental design for a fluid dispenser, as shown and described.

DESCRIPTION

FIG. 1 is a front elevational view of a fluid dispenser showing my new design;

FIG. 2 is a rear elevational view thereof;

FIG. 3 is a left side elevational view thereof;

FIG. 4 is a right side elevational view thereof;

FIG. 5 is top plan view thereof;

FIG. 6 is a bottom plan view thereof; and,

FIG. 7 is a top, front, and right side isometric view thereof. The broken lines in the drawings show portions of the dispenser which form no part of the claimed design.

1 Claim, 6 Drawing Sheets
